UNITED STATES PATENT OFFICE.

KNUD J. KNUDSEN, OF CHICAGO, ILLINOIS.

DOOR AND WINDOW STOP.

Application filed December 29, 1921. Serial No. 525,649.

To all whom it may concern:

Be it known that I, KNUD J. KNUDSEN, citizen of the United States, residing at Chicago, in the county of Cook and State 5 of Illinois, have invented a certain new and useful Improvement in Door and Window Stops, of which the following is a full, clear, concise, and exact description, reference being had to the accompanying drawings, 10 forming a part of this specification.

The invention relates to door and window stops, and is designed to provide a means whereby a tight and weather proof connection is produced and maintained between 15 a door and door frame or a window and window frame.

The invention has as an object the utilization of the strip known as a door "stop" or window "stop" (hereinafter referred to as 20 stop), of the ordinary door or window structure and to provide this stop with a simple and effective construction which permits ready movement of the stop relatively to the door or window. This construction allows 25 the stop to engage and hold the door or window so that wear, shrinkage, warping, etc., may be compensated for, resulting in a tight fitting and weather proof structure, and eliminating rattling of the door or window.

30 The utilization of the ordinary stop, which is part of the ordinary door or window construction, eliminates the necessity of providing an auxiliary device which would add to the expense of the structure without resulting in a corresponding increase in efficiency.

40 It is an object of the invention to construct the stop in such a manner that it may be moved at any time when found necessary without any great inconvenience and without necessitating the removal of any elements of the structure of the invention to effect an adjustment.

45 It is an additional object to provide an extremely simple arrangement whereby the stop may be securely held in any of its adjusted positions.

50 Another of the objects of the invention is to provide an arrangement which may be interchangeably employed for the stop ordinarily provided for the purpose of holding the door or window with respect to the door or window frame.

55 The invention will be explained particularly in conjunction with window sashes and a frame therefor. However, it will

be obvious that its association is not limited to this particular structure, as it is equally capable of association with a door and door frame. In the drawings, the invention is 60 shown in connection with both forms of structure. In the drawings, upper and lower window sashes and a window frame surrounding both window sashes are illustrated. The window sashes and frame are 65 of the usual character in which a stop is employed which is arranged on the interior of the frame, with respect to the room. The stop usually extends throughout the entire 70 length of the window frame, is secured to the inner face of the window frame, and usually has one edge abutting against the face of the window sash to hold the inner 75 face of the window sash in its proper position with respect to the frame. The stop is also used for the purpose of providing part of a guideway for the window sash and for maintaining it within the slideway. The stop has the further function of maintaining 80 the window sash against the parting strip arranged between the sashes in the frame.

To employ the invention the stop is provided with a plurality of transversely arranged slots with screws passing through the slots into the window frame. The slots permit the stop to be moved with relation to the window frame to vary the position of the stop with respect to the sash and the frame, to maintain the sash in its proper 90 position to effect a tight and weather proof connection between it and the frame, when the screws are tightened.

If so desired, the slots may be lined with 95 suitably elongated ferrule-like metallic members (hereinafter called ferrules) which correspond to the shape of the slots. The provision of the ferrules eliminates wear of the stop when the latter is moved with relation to the screws.

100 Washers may be provided upon the screws and arranged between the heads of the screws and the edges of the ferrules. Thus, when the screws are tightened, the pressure exerted thereby will be transmitted to the ferrules, which prevents the face of the adjustable stop having the slots from becoming marred by the pressure of the screws when the screws are tightened to hold the stop 105 with relation to the door or window frame.

110 The construction of the invention also permits any one, or all, of the stops to be bodily

removed from its, or their, association with the door or window frame, and thereby permits the removal of the door or window sash from the frame when this is found necessary or desirable.

In practice the door or window frame will be decorated by the application of paint or varnish prior to the association of the stop with the frame; thus, any movement 10 or adjustment of the stop will not cause an unsightly appearance of an unpainted or unvarnished surface which may be exposed when the stop is moved.

It is understood that the stop is provided 15 with a plurality of slots arranged at suitable intervals throughout the length of the strip. Thus, in the event that one of the window sashes is out of vertical alignment with the frame, by releasing the screws one 20 end of the stop may be moved with respect to the opposite end. The stop may also be set out of alignment with the window sash, that is, at an angle, in order to cause a binding action at the bottom of the window 25 sash and leave the balance of the sash out of contact and readily movable, if that be desired. Furthermore, the stop may be moved bodily toward and away from the window sash to accomplish the desired end. 30 The invention will be explained in conjunction with the embodiments thereof illustrated in the drawings, it being obvious that changes and modifications may be employed without departing from the spirit of the invention as expressed in the appended claim 35 forming a part hereof.

In the drawings,

Figure 1 is a plan section of fragments of window sashes and a frame therefor, showing 40 the invention applied thereto;

Fig. 2 is a plan section of a fragment of a door and door frame, showing the invention applied thereto;

Fig. 3 is a section taken on line 3—3 of 45 Fig. 1, looking in the direction of the arrows;

Fig. 4 is a detail view of the stop illustrated in Figs. 1, 2 and 3, showing the ferrule and also showing one of the screws in 50 section; and

Fig. 5 is an enlarged perspective view of the ferrule employed in the construction.

The structure shown in Fig. 1 illustrates 55 the use of a window sill 10 in a window frame generally designated 11, and upper and lower window sashes 12 and 13, respectively, which are slidably arranged within the window frame 11. The window frame 11 is finished with the inner and outer casings 14 and 15, the stationary outer strip 16 and the parting strip 17. The parting strip 17 is arranged between the window sashes 12 and 13. The space between the strips 16 and 17 produces a slideway 18 for 60 the window sash 12. The strips 16 and 17

are secured in position with relation to the window frame 11 in any suitable manner. The strip 17 cooperates with the stop 19 to provide the slideway 20 for the window sash 13. The stop 19 extends around the 70 sides and top on the inner face of the window frame, and in some cases extends along the lower portion of the window sash.

As stated, it is an object of the invention to provide the stop 19 with a structure 75 whereby it may be moved with relation to the window frame structure 11 and with relation to the window sashes 12 and 13 to compensate for any wear, shrinkage, warping and looseness of the parts of the window 80 structure. A tight connection between the window sashes and the frame is produced which eliminates vibration and rattling of the window sash and produces a tight, weather proof connection between the window sashes and the frame.

To accomplish these ends, the stop 19 is provided with a plurality of slotted apertures 21 which are disposed at suitable intervals throughout its entire length. The 90 slots 21 are arranged transversely to the length of the stop. A screw 22 is employed and passed transversely through each of the slots 21 into the portion 23 of the window frame generally designated 11. One dimension of the slot is less than the dimension of the head 24 of the screw 22, which prevents the stop 19 from becoming 100 separated from the window frame when secured thereto by the screws, yet permits the stop to be adjusted and held in its adjusted position.

Each of the slots 21 is preferably provided with an elongated metallic ferrule 25 which substantially corresponds to the dimensions of the slot 21. The ferrule is provided to prevent wear of the stop 19 at the slots and has the additional function of relieving the face of the stop 19 of the pressure exerted by the head of the screw when the latter is screwed into the portion 23 of the window frame to secure the strips in 110 adjusted position. As pressure is applied to the edge of the ferrule instead of directly upon the face of the stop, the stop 19 is prevented from becoming marred, yet is securely held in its adjusted position with relation to the door or window frame.

A washer 26 may be employed and interposed between the head 24 of the screw 22 and the adjacent edge of the ferrule 25. The washer 26 may be of any desired shape, and therefore may be of a length sufficient to extend beyond the opening of the ferrule 25 and hide the opening, thus improving the 115 appearance of the structure.

It is evident that by releasing the screws 22 which hold the stop 19 with relation to the window frame, the stop may be moved bodily to any desired position relatively to 120 125 130

the window sash, and after the screws are drawn up, the stop is securely held in its adjusted position. It is also manifest that upon the release of the screws one end only of the stop may be moved to effect an adjustment thereof with relation to the window sash and frame.

It is also obvious that if it is desired to remove the window sash from within the frame the stop may be bodily removed to permit the removal of the window sash from within the frame.

As before stated, the face of the frame portion 23 adjacent the movable stop 19 will be decorated prior to the association of the stop with the window frame, which prevents exposing an unfinished surface upon the adjustment of the stop relatively to the face of the window frame.

By referring to Fig. 2, it is evident that a stop such as 27, which is attached to the door jamb 28, may be also supplied with the invention heretofore described in connection with the structure shown in Fig. 1 and thus produce the necessary tight connection between the door jamb and the door 29 when the latter is closed.

From the foregoing description it is evident that the structure of the invention is capable of association with any door or window frame, and is capable of attachment and adjustment without any great incon-

venience, as all that is necessary to apply the device is to remove the stops of the door or window structure and substitute the stop having the structure of the invention.

Having thus described the invention, what I claim and desire to secure by Letters Patent is:

A stop of the character described having an aperture and an elongated ferrule with parallel sides arranged in, and with its parallel sides extending the entire depth of the aperture to permit the adjustment of the stop relatively to the frame with which the stop is adapted to be associated, and with respect to a holding element which is passed through the opening in the ferrule, which holding element has a portion which engages one edge of the ferrule, the other edge of the ferrule being arranged relatively to that face of the stop which is immediately adjacent to the frame so that said last mentioned edge of the ferrule may directly engage the frame and thereby relieve the stop of the holding force applied by the holding element and apply said force to the frame and ferrule.

In witness whereof, I hereunto subscribe my name this 23rd day of December A. D., 1921.

KNUD J. KNUDSEN
